UNITED STATES PATENT OFFICE.

ZERA J. MASSEY AND JESSE H. GRAMMER, OF LOIS, TENNESSEE.

WHIFFLETREE-HOOK.

SPECIFICATION forming part of Letters Patent No. 689,734, dated December 24, 1901.

Application filed July 18, 1901. Serial No. 68,771. (No model.)

To all whom it may concern:

Be it known that we, ZERA J. MASSEY and JESSE H. GRAMMER, citizens of the United States, residing at Lois, in the county of Moore 5 and State of Tennessee, have invented certain new and useful Improvements in Whiffletree-Hooks; and we do declare the following to be a full, clear, and exact description of the invention, such as will enable others skilled in the art to which it appertains to make and use 10 the same.

The invention relates to whiffletree-hooks.

The object of the invention is to provide a simple, durable, and inexpensive hook which 15 will reduce to a minimum the liability of the trace-ring becoming accidentally disengaged therefrom and which will overcome the serious objections to hooks which project some distance away from the end of the whiffletree.

With this and other objects in view the invention consists of certain novel features of construction, combination, and arrangement of parts, which will be hereinafter more fully described and more particularly pointed out 25 in the appended claim.

In the accompanying drawings, Figure 1 is a perspective view taken from the rear of one end of the whiffletree, illustrating the application of our invention. Fig. 2 is an end 30 view, and Fig. 3 is a cross-sectional view, to illustrate the curved rear wall.

In the drawings, 1 denotes a sleeve, which may be of any length desired and which is adapted to be slipped upon and secured in 35 any suitable manner to the end of the whiffletree. The outer end of this sleeve is provided with a shoulder 4, while the rear side is provided with an enlargement 5, formed with a curved recess 6, the arc of which corresponds 40 to that of the trace-ring 7. A guard-tongue 8, formed integral with the outer end of the sleeve, extends laterally and projects immediately at the rear of the curved recess. In

placing the ring upon the hook it is turned rearwardly, so as to have its convex surface 45 engage the concave surface of the recess. It is slipped under the tongue and then swung around on the outer end of the sleeve and bears against the shoulder thereof. The ring cannot become disengaged from the hook until it has been turned entirely around, so that 50 its convex surface will register with the recess, when it may be easily removed. Should it slip or cant downwardly, it will be prevented from falling off the end of the hook by 55 reason of the guard-tongue. This tongue also serves to afford means for guiding the trace-ring in operative position.

From the foregoing description, taken in connection with the accompanying drawings, 60 the construction, mode of operation, and advantages of our invention will be readily understood without requiring a more extended explanation.

Various changes in the form, proportion, 65 and details of construction may be made within the scope of the invention without departing from the spirit or sacrificing any of the advantages thereof.

Having thus described our invention, what 70 we claim, and desire to secure by Letters Patent, is—

A whiffletree-hook consisting of a body portion having a shoulder at one end and having a curved recess at its rear side, and a tongue 75 extending inwardly from the outer end of the body portion immediately at the rear of the curved recess, substantially as set forth.

In testimony whereof we have hereunto set our hands in presence of two subscribing witnesses.

ZERA J. MASSEY.
JESSE H. GRAMMER.
